UNITED STATES PATENT OFFICE.

WILLIAM B. TURNER, OF NEW YORK, N. Y., ASSIGNOR OF ONE-HALF TO
DR. CORNELIUS BEARD, OF SAME PLACE.

AUTOMATIC CAR-BRAKE.

SPECIFICATION forming part of Letters Patent No. 278,834, dated June 5, 1883.

Application filed February 5, 1883. (No model.)

To all whom it may concern:

Be it known that I, WILLIAM B. TURNER, a citizen of the United States of North America, and a resident of the city, county, and State of New York, have invented a new and useful Improvement in Automatic Momentum Car-Brakes, of which the following is a specification.

The object of this invention is to provide an improvement on the automatic car-brake for which I filed an application for a Patent of the United States December 15, 1882, Serial No. 79,374.

The invention consists in the combination, construction, and arrangement of parts hereinafter more fully described, and then pointed out in the claims.

Reference is to be had to the accompanying drawings, forming part of this specification, in which similar letters of reference indicate corresponding parts in all the figures.

Figure 1 is a partly sectional side elevation of a portion of a car-frame with my improved brake applied. Fig. 2 is a plan view of the same, partly broken away to show that portion of the mechanism below the line $\alpha\alpha$ in Fig. 1. Fig. 3 is an enlarged partly sectional side elevation, showing my improved axle, collar, and dog. Fig. 4 is an enlarged partly sectional side elevation of my improved attachment for applying the brakes to the rear portion of a train in the event of its breaking loose from the forward portion. Fig. 5 is an enlarged rear elevation, showing the relative positions of the draw-bar pitman and operating-lever when engaged with each other. Fig. 6 is a sectional plan view of the draw-bar pitman. Fig. 7 is a side elevation of cam-rods connected with the operating-lever.

In the drawings, A represents a car-frame; B B', the front and rear axles; and C C', the front and rear wheels, respectively, of a car-truck.

On the draw-bar D are spring-plates a a' , between which, about the draw-bar shank, is a spiral spring, b.

Fixed upon the draw-bar shank is a clevis, E, embracing the plates a a' , and held in place by draw-bar shoulder c at one end, and by pin d, passing through the draw-bar shank at the other end.

To an eyebolt, f, secured to the rear end of the clevis E, is attached the draw-bar pitman F, whose forked rear end is designed to engage over the head of the operating-lever G, 55 said pitman being restricted in lateral movement by a yoke, g, that rises from the frame H, which supports the operating-lever fulcrum and is bolted to the car-body timbers I I, as shown in Fig. 5. This pitman F is composed 60 of two sections, one telescoping within the other. The rear section, having the forked end designed for engaging the operating-lever G, is tubular, with opposite slots, f' f'' , in its sides, and contains a spiral spring, f^2 , while 65 the front section, that is connected with the clevis E, is a solid bar or rod, which is entered into the rear section to bear upon the spring f^2 , and is held in place by a pin, f^3 , passing laterally through it and extending into the 70 slots f' f'' . It will be seen that if excessive force be applied in compressing the draw-bar the spring f^2 will yield and prevent the injurious transmission of said force to the other parts of the brake mechanism. In the extension of the draw-bar the pin f^3 of the front section of the pitman F engages with the forward end of the slots f' f'' , and on the compression of the draw-bar the spring f^2 transmits the motion of the forward pitman-section to the rear 75 section thereof, the slots f' f'' allowing for these movements of the forward pitman-section.

Projecting laterally from the lever G are pins or stops h h, on which the rear ends of the cam-rods K K are designed to rest, and on 80 the rear ends of rods K K the rear end of the pitman F rests, excepting when it is disengaged from the operating-lever G.

Between the plates of the frame H, which is secured to the timbers of the car-body, is secured the fixed fulcrum L of the operating-lever G. The lower end of the operating-lever G is pivoted to a horizontal pitman, M, whose eyed forward end encircles the shaft N' of the friction-pulley N, which pulley N is designed, 90 when required, to be forced into contact with the axle collar or pulley B'. One end of the shaft N' is journaled in a slot, k, of the frame N' on the car-truck, so as to have freedom of motion toward and from the car-axle B. On 95 said axle B is rigidly fixed a collar or friction-pulley, B', in the periphery of which, near one

end thereof, is formed a socket, l , as shown in Fig. 3. More than one socket l may be formed therein without departing from my invention.

Pivoted at its lower end on one of the plates 5 of the frame N^2 is the rocking or adjusting lever O , to which is pivoted a dog, P , that is provided with two teeth, m m' , respectively, and extends forward over the axle-collar B^2 and rests thereon. To the upper end of this 10 rocking or adjusting lever O are pivoted two cam-rod, K K , each provided with a cam or tooth, n , and extending rearward and resting on the lateral stops or pins h h of the operating-lever G .

15 The brake-beams Q and shoes Q' are of the ordinary kind, as are the brake-lever R , brake-connecting rod R' , and brake-chain R^2 , the latter having one end connected to the lever R and the other end to the friction-pulley shaft 20 N' , said chain passing over a supporting-roller, R^3 .

As shown in Fig. 1, the brakes are in the disengaged position they would assume if the car were being pulled in the direction of the 25 arrow and the draw-bar were extended. Now, if the engineer wished to stop the train, he would slow the engine, with the effect of compressing the draw-bar D . This compression of the draw-bar D forces the pitman F , and 30 consequently the head of the operating-lever G , rearward, whereby, through the medium of the pitman M , the friction-pulley N is brought into contact with the axle-pulley B^2 , and the chain R^2 at once begins to be wound up on the 35 shaft N' , with the effect of applying the brakes. The train being stopped, if now the engine is moved forward the consequent extension of the draw-bar operates to disengage the brakes by withdrawing the pitman F from the top of 40 the lever G , thereby permitting the relaxation of the tension of the brake-beams, brake levers and chain, and rod, operating to withdraw the friction-pulley N from contact with the axle-pulley B^2 , which pulley N is then free to 45 revolve in the direction opposite to that in which it was wound up, and disengage the brakes. (The pitman M may be pulled rearward by a spring for the purpose of withdrawing the pulley N from contact with the axle-pulley B^2 , as 50 set forth in my previous application for patent above referred to.) Then, if the car is backed, the compression of the draw-bar, operating through the pitman F , presses the top of the operating-lever G rearward, which, through 55 the pitman M , brings the friction-pulley N in contact with the axle-collar B^2 . Then as the wheels begin to revolve backward, the chain R^2 begins to be wound up; but in the continued 60 revolution of the car-axle, and as soon as the socket l of the collar B^2 comes opposite or beneath the dog-tooth m , the latter falls by the gravity of the said dog P and engages in said socket l , and the further revolution of the collar B^2 consequently forces the head of the rocking or adjusting lever O rearward, and, in consequence, the cam-rod K K are pushed rearward, so that their cams or teeth n n are forced

up over and beyond the pins or stops h h of the operating-lever G . In this rise over said stops h h the cams-rod K K elevate the rear end of the pitman F above the top of the lever G , and the pitman F being thus disengaged from the operating-lever G the compression of the draw-bar will consequently fail to operate for applying the brakes, and the car may be 70 freely run backward. Now, in order to bring the pitman F into the position required for the application of the brakes, (for the flattened portion of the rear end of said pitman is now resting on the head of the operating-lever G ,) the draw-bar D must be pulled out sufficiently to 75 slightly compress the spring b , when the fork of said pitman falls over and re-engages with the said operating-lever head. If now it is desired to go ahead, the draw-bar is pulled out 80 by the forward movement of the engine, and, as the axle B rotates forward, the dog-tooth m' falls and engages in the axle-collar socket l , whereby the upper end of the rocking or adjusting lever O is drawn forward with the effect of drawing the cam-rod K K forward, with 85 their cams or teeth n n in front of the operating-pins h h . The pitman being at this time drawn out by the action of the draw-bar, it will be in a position to act upon the lever at 90 the next backward movement of the draw-bar, and thus operate the brakes.

The attachment to the brake mechanism whereby the brakes may be automatically applied to the rear portion of a train that breaks 95 loose from the forward portion or engine consists of a pitman, S , having its forward end slotted, as shown at o , and embracing the friction-pulley shaft N' , and pivoted at its rear forked end to the lower end of a toggle or eccentric lever, T , forward of the center thereof, as shown at p . That part of the eccentric portion of the lever T which projects rearward is pivoted, as shown at q , between the lugs of a spring cover or case, U , which is held on the forward end of a spiral spring, V . Said case U and spring V , both being held in a box, W , that is open at front and top, and is formed in the frame N^2 , form a spring or yielding fulcrum. The upper end of the lever T may be forked, 105 as shown at s , with which it is designed to engage the rear extremity of a rod or chain, X , as shown in Fig. 1.

When the cars to which this device is applied are uncoupled the rod or chain X is designed to be in the position shown in full lines, Fig. 1, with the chain or rod ring t engaged over a hook, v , fixed in a timber of a car, and when the cars are coupled the ring t is to be disengaged from the hook v and the ring u will 115 be engaged over a hook (not shown) fixed on a timber of the car next preceding, so that in a train, each car will be connected with the other and with the engine by a chain or rod, X , which will hang slack between them when the train is in motion, and the toggle-lever attachment will be in the position shown in Fig. 1, and in dotted lines, Fig. 4, in which position no pressure is exerted by said attachment 120 125 130

upon the friction-pulley shaft N'. Now, then, should a rear car break loose, there would in consequence be a pull on the chain or rod X sufficient to pull the head of the toggle-lever

5 T forward, as shown in full lines, Fig. 4, whereby the pitman S is forced forward against the friction-pulley shaft N', with the effect of forcing the pulley N in contact with the axle-collar B² and holding it there, for when the toggle-lever T is brought into this position, with the pivot p below the plane of the pivot q, as shown in Fig. 4, the device is locked fast, holding the pulleys N B² in constant contact, so that continued revolution of the axle B in either 15 direction will cause the shaft N' to revolve and wind up the chain R² and so apply the brakes. This auxiliary brake-applying device or attachment may be again rendered inoperative or set ready for action by simply pushing the 20 head of the lever T back to its original position by means of its attached rod or by other means.

It will be observed that as the fulcrum H of the operating-lever G is secured to the car-body the relative positions of the said lever G and the draw-bar D are always maintained, even when the car-body overruns the truck on application of the brakes.

Any novel feature shown herein, and not 30 claimed, I reserve the right to make the subject of a separate application.

Having thus described my invention, I claim as new and desire to secure by Letters Patent—

1. In a car-brake, the combination, with the 35 draw-bar and its spring-plates and the draw-bar pitman, of a clevis attached to the pitman, substantially as herein shown and described, arranged on the draw-bar shank, and embracing said draw-bar spring-plates, whereby said 40 clevis is made operative on the pitman in both directions of the draw-bar motion, substantially as set forth.

2. In a car-brake, the combination, with a 45 draw-bar, of a telescopic forked pitman constructed of two sections, one sliding within the other, one of said sections provided with a slot in which works a pin from the opposite section, and a spring contained within one of said sections and operating on the other, substantially 50 as described.

3. In a car-brake, the combination of the 55 friction-collar and a friction-wheel with a pivoted elbow-lever and a pitman having one end pivoted to the bend of said lever and its other end acting on the shaft of the friction-wheel,

and a connection constructed to bring one arm of the lever in line with the pitman and lock the friction-pulley in an operative position, substantially as described.

4. The combination, with a friction car-brake apparatus, of a toggle-lever adapted to hold the friction device in contact when in one position, of a connection with said toggle-lever, having one end adapted to be secured to the next adjacent car and its other end to the 60 lever, and arranged to retain its hold upon the lever when the friction device is inoperative, and to slip off when said friction device is brought into operation, substantially as described. 65

5. The combination, with the collar B², of the friction-wheel N', pitman S, having one end connected directly to the axle of the friction-wheel and its other end connected to an elbow-lever, T, and a connection having one 75 end loosely attached to the end of the lever T and adapted to slip therefrom when the position of said lever is changed, and its other end adapted to be engaged with the next car, substantially as described. 80

6. In a momentum car-brake, the combination, with the car-axle, of a pulley or collar fixed thereon, having a peripheral socket and a dog for operating the brake-tripping device, provided with two teeth facing in opposite directions and adapted to engage with the opposite sides of said socket, substantially as described. 85

7. In a car-brake, the combination of the operating-lever C, pitman F, operated by the 90 draw-bar, the lever O, operated through suitable connections by the motion of the car-axle, and the cam-rod K connected to the lever O and operating directly upon the pitman, substantially as described. 95

8. In a car-brake, the combination, with the draw-bar pitman, operating-lever, and axle-collar, of a rocking lever having a doubly-toothed dog and a cam-rod pivoted thereto for breaking connection between said pitman and 100 operating-lever, as set forth.

In testimony that I claim the foregoing as my invention I have signed my name, in presence of two witnesses, this 2d day of February, 1883.

WILLIAM B. TURNER.
